UNITED STATES PATENT OFFICE.

JOHN H. LAKEY, OF TURNER, ASSIGNOR TO GEORGE W. BILLINGS, OF CHICAGO, ILLINOIS.

IMPROVEMENT IN RAILROAD FROGS.

Specification forming part of Letters Patent No. 137,085, dated March 25, 1873.

To all whom it may concern:

Be it known that I, JOHN H. LAKEY, of Turner, in the county of Du Page and State of Illinois, have invented a certain new and Improved Railway Frog; and I do hereby declare that the following is a full, clear, and complete description of the same, reference being had to the accompanying drawing making part of this specification.

Figure 1 is a plan view of the frog. Fig. 2 is a side view. Fig. 3 is an end view.

Like letters of reference refer to like parts in the several views.

The nature of this invention relates to a railway frog; and the object thereof is to secure the two ends of the rails together of which the frog is constructed so that they cannot become separated—an event to which all frogs of this class are liable, but which defect is removed when the rails are secured to each other in the manner as follows.

In the drawing, A represents the ties on which the rails B C are laid and thereto secured. The ends of said rails are fitted to each other, forming a tapering point, D, and are secured thus by flat keys *a*, Fig. 2, inserted

in corresponding holes cut through the web of the two rails.

The ordinary way of securing the rails together is by the use of round iron bolts. These are very liable to be cut off by the edges of the bolt-holes in consequence of the vertical movement of the rails caused by the passing train, which thereby act like a pair of shears on the bolts. To prevent this cutting the bolts I use in place thereof the flat key *a* referred to, the advantage of which is that it presents a larger bearing-surface to the vertical movement of the rail than a bolt; hence such movement is partially prevented, and the keys remain uncut or uninjured in consequence of their broad flat surface.

Claim.

What I claim as my invention, and desire to secure by Letters Patent, is—

The broad flat key or keys, as above described, in combination with the rails B C of a railway frog, substantially in the manner as and for the purpose set forth.

Witnesses: JOHN H. LAKEY.
